US0D1072163S

(12) **United States Design Patent** (10) **Patent No.:** **US D1,072,163 S**
(45) **Date of Patent:** **** Apr. 22, 2025**

(54) **FUEL WATER SEPARATOR**

(71) Applicant: **Wuhu Tianhao E-commerce Co., Ltd.,**
Anhui (CN)

(72) Inventor: **Zhenzhen Li**, Anhui (CN)

(**) Term: **15 Years**

(21) Appl. No.: **29/836,407**

(22) Filed: **Apr. 27, 2022**

(51) **LOC (15) Cl.** **23-01**

(52) **U.S. Cl.**

USPC **D23/209**

(58) **Field of Classification Search**

(57) **CLAIM**

The ornamental design for a fuel water separator, as shown
and described.

DESCRIPTION

FIG. 1 is a perspective view of the fuel water separator
showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent portions
of the fuel water separator that form no part of the claimed
design.

1 Claim, 8 Drawing Sheets
